UNITED STATES PATENT OFFICE.

ROBERT WILSON, OF McALEVY'S FORT, PENNSYLVANIA.

IMPROVEMENT IN WATER-WHEELS.

Specification forming part of Letters Patent No. 155,690, dated October 6, 1874; application filed April 18, 1874.

To all whom it may concern:

Be it known that I, ROBERT WILSON, of McAlevy's Fort, in the county of Huntingdon and State of Pennsylvania, have invented a new and valuable Improvement in Water-Wheels; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a horizontal section of my water-wheel, and Fig. 2 is a transverse sectional view of the same. Fig. 3 is a detail view.

This invention has relation to water-wheels of the horizontal kind, wherein a number of scrolls and chutes are employed for the purpose of directing water to the surface of the buckets.

The object of the invention is to provide a wheel whose buckets shall have suitable form and shall bear proper geometrical relations to their entering and discharging mouths; and it consists in constructing each bucket in the shape of a quarter of a cylinder, whose radius is equal to the distance between the outer and inner edges of the wheel-rim, and whose axis is vertical, intersecting the outer edge of said wheel-rim, and coincides with a radial plane of the wheel passing through the inner edge of the bucket.

In the accompanying drawings, the letter A designates the upper, and B the lower, rim or plate of my wheel. C C designate the buckets, which are preferably of wrought-iron. Each bucket is very nearly a quarter of a cylinder, and is applied between said rims or plates, with its axis vertical and its concavity in the direction of the mouths of the feeding scrolls and chutes. The axis of each bucket intersects the outer edges of the wheel-rims, and is coincident with a plane radiating from the center of the wheel and passing the inner

edge of said bucket. The radius of curvature of the bucket is equal to the distance between the outer and inner edges of the wheel-rim. Hence each bucket is truly tangent to the inner surface of the wheel, and intersects its outer surface very nearly at right angles.

In a wheel of twenty inches diameter the radius of the inner edge of the wheel-rim will be seven inches. The rim will be three inches in width, and three inches will be the radius of curvature of the bucket. By observing the rules of construction above laid down the tangential position of the buckets to the inner or discharging surface of the wheel will be readily secured, with the following results: The water brought to the wheel in ducts, commonly called scrolls and chutes, is dashed against the concavities of the buckets, causing the wheel to revolve. After the water has expended its force upon the bucket its course is turned in the direction of the inner curve of the bucket, avoiding the convex lower end of the next bucket, or so slightly impinging against it as in no degree to impede or obstruct the revolution of the wheel by the "backwater."

Having thus described my invention, what I claim, and desire to secure by Letters Patent, is—

The water-wheel having the radiiuses of its entering and discharging surfaces as 10 to 7, and equidistant buckets, each a quarter cylinder, whose radius of curvature is equal to the parallel distance between said entering and discharging surfaces, and whose axis is at said entering-surface and coincident with a radial plane passing through the discharging-edge of said bucket, as specified.

In testimony that I claim the above I have hereunto subscribed my name in the presence of two witnesses.

ROBERT WILSON.
